UNITED STATES PATENT OFFICE

156,321

FITTING RING CONTAINER

Leo Coel, New York, N. Y., assignor to Holland-Rantos Company, Inc., New York, N. Y., a corporation of New York

Application January 3, 1949, Serial No. 9

Term of patent 14 years

(Cl. D80—5)

To all whom it may concern:

Be it known that I, Leo Coel, a citizen of the United States, residing at 2157 Holland Avenue, Bronx, New York, have invented a new, original, and ornamental Design for a Fitting Ring Container, of which the following is a specification, reference being had to the accompanying drawing, forming part thereof.

In the drawing:

Fig. 1 is a perspective view of the fitting ring container showing my new design.

Fig. 2 is a perspective view of same with cover lifted showing the interior design.

Fig. 3 is a bottom plan view of the container showing my new design.

I claim:

The ornamental design for a fitting ring container, substantially as shown.

LEO COEL.
